DISPLAY CABINET

Charles W. Long, Philadelphia, Pa.

Application January 23, 1953, Serial No. 23,276

Term of patent 14 years

(Cl. D80—11)

To all whom it may concern:

Be it known that I, Charles W. Long, a citizen of the United States, residing at Philadelphia, Pennsylvania, have invented a new, original, and ornamental Design for a Display Cabinet, of which the following is a specification, reference being had to the accompanying drawing, forming a part hereof.

Fig. 1 is a front elevational view of a display cabinet, embodying the design.

Fig. 2 is a top plan view, and

Fig. 3 is a perspective view thereof.

The display cabinet includes a curved, transparent or translucent front wall the outline of which is indicated in Fig. 3.

I claim:

The ornamental design for a display cabinet, as shown and described.

CHARLES W. LONG.
